BY Chas. M. Bump

Geo. B. Willcox, ATTORNEY.

UNITED STATES PATENT OFFICE.

CHARLES MURRAY BUMP, OF BAY CITY, MICHIGAN.

FURNACE.

SPECIFICATION forming part of Letters Patent No. 650,821, dated June 5, 1900.

Application filed February 15, 1900. Serial No. 5,267. (No model.)

To all whom it may concern:

Be it known that I, CHARLES MURRAY BUMP, a citizen of the United States, residing at Bay City, in the county of Bay and State of Michigan, have invented certain new and useful Improvements in Furnaces; and I do hereby declare the following to be a full, clear, and exact description of the invention, such as will enable others skilled in the art to which it appertains to make and use the same.

My invention relates to furnaces, and pertains more particularly to water-heating furnaces.

The improvements consist in certain constructions and devices in a furnace whereby the objects of my invention are accomplished. These objects are, first, to provide a furnace with two fuel-burning compartments communicating with each other in such manner that the gases of combustion from either compartment may be passed over the coal-bed in the other compartment, where they are mixed with air and burned; second, to provide means for readily changing the current of gases from one compartment into the other; third, to provide a partition-wall between the compartments that shall consist of a water-heating surface and act not only as a partition or bridge wall over which the gases pass, but also to deflect the gases coming from one compartment downward against the coal-bed in the other compartment, thereby increasing the efficiency of the heating-surface in the partition and also securing more perfect combustion.

The invention is clearly shown in the accompanying drawings, throughout the views of which similar characters of reference designate corresponding parts and devices.

Figure 1 is a part-vertical section of my improved furnace applied to a house-heater, the section being parallel with the front of the furnace. Fig. 2 is a vertical section taken longitudinally through one of the fuel-compartments on the line y y of Fig. 1.

The device consists in a furnace-body 1, that may be surrounded with a water-space 2, which communicates with the water circulation of the furnace-shell, having a central partition 3 extending the length of the furnace and communicating at its ends with the water-space surrounding the furnace-body. Near its upper part the central partition 3 has an opening 4, which connects the two compartments. At the top of the partition 3

and communicating therewith are laterally-extending wings or deflectors 5 and 5^a, which project over the respective compartments, except for a smoke-outlet 6 or 6^a at each side, upon which draft-regulators 7 and 7^a may be closed by means outside the furnace.

The operation of the furnace is as follows: There being a bed of incandescent coals in one compartment, fresh coal is added to the fire in the other compartment, the draft-regulator 7^a of which is then closed. The smoke and gas of the new fire pass through the opening 4 into the other compartment, where they are deflected by the wing 5 downward against the incandescent-coal bed. Air is at the same time admitted above the incandescent coal by any suitable means, and the smoke and volatile gases are thereby consumed, the remaining gases passing into the furnace-shell through the opening 6. When fresh coal is added to the compartment containing the bright-coal bed, the draft or damper 7 is closed and the damper 7^a is opened, thereby reversing the direction of the gases and consuming the smoke in the other compartment.

What I claim is—

1. In a water-heating furnace the combination with a grate of a vertical water-containing partition dividing the grate-surface into two parts; a gas-passage through said partition; a water-containing top for said partition extending laterally over the fire; and dampers for regulating the gas-exit between the laterally-extending top and the furnace-wall, substantially as described.

2. In a water-heating furnace the combination with a grate of a vertical water-containing partition dividing the grate-surface into two parts and communicating with a water-space surrounding the furnace; an opening through said partition; a water-containing top for said partition, communicating with the water-space surrounding the furnace and extending laterally over a portion of the fire-bed on each side of the partition; and dampers for regulating the gas-exit between the laterally-extending top and the furnace-walls, substantially as described and for the purposes set forth.

In testimony whereof I affix my signature in presence of two witnesses.

CHARLES MURRAY BUMP.
